MINING APPARATUS

Thomas E. Pray, Chicago, Ill., assignor to Goodman Manufacturing Company, Chicago, Ill., a corporation of Illinois

Application June 22, 1936, Serial No. 86,546

13 Claims. (Cl. 262—12)

This invention relates to improvements in mining apparatus and has as its principal objects to provide an expansible coal breaking device which is supported in a novel manner so that it may be inserted in or withdrawn from, or may be positioned at various points along a kerf in the coal face by power.

Heretofore coal breaking devices consisting of a flexible expansible member have been used for breaking down coal in mines, but these devices have been of a rather bulky construction, making it difficult to insert or withdraw them from the kerf, with the result that their practical application has been limited. Another disadvantage of these devices is that the expansible member frequently ruptures, particularly at the point where fluid is admitted thereto, which causes the means for admitting fluid to the member to be torn therefrom. This is caused by the fact that the expansible member suddenly expands after the coal has been broken down, due to the release of pressure thereon from the outside and the continued application of pressure on the inside and the fact that it has not heretofore been possible to adequately secure the means for admitting fluid under pressure to the expansible member.

The device of my invention is so arranged as to eliminate these difficulties, by adjustably mounting the expansible member in advance of a self-propelled truck in a novel manner and by providing an improved means of a novel construction for admitting fluid under pressure to said expansible member which may be more adequately secured to said member than formerly, together with a means for limiting expansion of said member beyond a certain predetermined point.

Other objects of my invention will appear from time to time as the following specification proceeds.

My invention may be more clearly understood with reference to the accompanying drawings wherein:

Figure 1 is a top plan view of a coal breaking apparatus constructed in accordance with my invention;

Figure 2 is a fragmentary side elevation of the device shown in Figure 1 with parts broken away and shown in longitudinal section;

Figure 3 is an enlarged fragmentary plan view of the device shown in Figure 1 with parts broken away and shown in substantially horizontal section;

Figure 4 is an enlarged fragmentary sectional

view taken substantially along lines 4—4 of Figure 3;

Figure 5 is an enlarged fragmentary sectional view taken substantially along lines 5—5 of Figure 3;

Figure 6 is an enlarged fragmentary sectional view taken substantially along lines 6—6 of Figure 3;

Figure 7 is an enlarged fragmentary sectional view taken substantially along lines 7—7 of Figure 1 showing certain details of the means for supporting and closing the ends of the coal breaking member; and

Figure 8 is a diagrammatic view showing the fluid pressure circuit to the coal breaking member.

In the drawings the embodiment of my invention illustrated includes a track mounted truck 10 having a turntable 11 at the forward end thereof which is provided with a pair of parallel spaced vertically extending guides 12, 12 which form an adjustable support for an elevating frame 13. Said elevating frame in turn is provided with a pair of parallel spaced support members 14 extending a substantial distance in advance of said truck, which support members form a supporting means for a flexible coal breaking member generally indicated by reference character 15.

The truck 10 is of an ordinary construction so will not herein be shown or described in detail, and is provided with a propelling motor 16 (see Figure 10). Said propelling motor serves as a means for driving the supporting track wheels of the truck and moving the truck along the track, for inserting or withdrawing the coal breaking member 15 from a kerf in the coal face or propelling said truck from working place to working place by means of a suitable system of gearing not herein shown or described since it is no portion of my present invention. Said motor also provides a drive means for turning the turntable 11 through a suitable system of gearing, which is not herein shown or described since it is no portion of my present invention, for positioning the coal breaking member at various points in the kerf along the coal face.

The elevating frame 13 is guided for vertical movement along the parallel spaced guides 12, 12 in a manner well known to those skilled in the art, and is held in engagement therewith by retaining strips 17, 17 secured to said elevating frame by suitable cap screws. A pair of parallel spaced shafts 19, 19 are mounted on opposite sides of said elevating frame. Each of said shafts has a pair of spaced pinions 20, 20 mounted thereon adjacent opposite ends thereof which mesh

with suitable racks extending upwardly along said parallel spaced guides.

The shafts 19, 19 are driven from a transversely extending shaft 21 by means of worm and worm gear trains generally indicated by reference characters 22, 22. Said transversely extending shaft is selectively driven from a motor 23, mounted on said elevating frame, and extending rearwardly therefrom, by means of a motor pinion 24 which 10 meshes with and drives a spur gear 25 on a longitudinally extending shaft 26 (see Figure 3). A helical gear 27 is keyed on said shaft intermediate the ends thereof and meshes with and drives a helical gear 28 keyed on a sleeve 29 freely 15 mounted on the transversely extending shaft 21. Said sleeve is operatively connected with said shaft by means of a suitable clutch member 31 herein shown as being of the friction cone type. The worm and worm gear trains 22, 22 may be of 20 the usual self locking type to hold said elevating frame in fixed relation with respect to the parallel spaced guides 12, 12 when the motor 23 is disconnected from the transverse shaft 21.

The support members 14, 14, as herein shown, 25 are formed from angle irons having depending legs 34, 34 extending along the elevating frame 13 and secured thereto at their rearward ends in a suitable manner. Said angles are of such a size that they may be inserted in a kerf in the 30 mine wall and extend forwardly from said frame in parallel relation with respect to the truck. The forward ends of said support members have the depending legs 34, 34 cut away to form a relatively flat supporting strip, herein shown as engaging the upper side of each outer end of a 35 flexible bag 33 of the coal breaking member 15.

The flexible bag 33, as herein shown, is preferably made from a flat hose or tube of a rubber and fabric material such as is commonly used in 40 heavy duty hoses of various types, and is so formed as to be relatively flat when deflated, and expandible to a substantially circular cross section adjacent the center thereof when inflated. Said bag extends transversely of the support 45 members 14, 14 and its ends are clamped together to prevent fluid under pressure from escaping therethrough. The means for clamping the ends of said bag together consist of the flattened ends of said support members which engage and are 50 clamped against the upper sides thereof, and clamping members 35, 35 engaging the lower sides thereof and engaged therewith by means of suitable nuts and bolts 36, 36 extending therethrough and through the ends of said support members 55 (see Figures 3, 4 and 7).

The clamping members 35, 35, as herein shown, each include a portion 38 adapted to be secured to the under side of the supporting member 14 in a suitable manner, which has a clamping strip 60 39 extending forwardly from the lower side thereof. Said clamping strip abuts and is secured to the under side of the bag 33 by means of the nuts and bolts 36, 36 so as to form a means for closing said bag, which clamps said bag against the support members 14, 14 and forms a rigid support therefor.

A manifold 40 is provided for admitting fluid under pressure to the bag 33. As herein shown, said manifold comprises a hollow member 42 closed at its ends by closure members 43, 43. One side of said member abuts an edge of the bag 33 and has a plurality of apertures extending through its side adjacent said bag. The edge of the bag 33 is likewise provided with a plurality 75 of apertures adapted to register for engagement

with the apertures in the member 42. An inner engaging member 44 is provided to engage the inside of said bag adjacent the member 43 (see Figures 3 and 5). Said inner engaging member is provided with a plurality of apertures there- 5 in adapted to register with the apertures in the edge of said bag and the member 42. Suitable hollow cap screws 45, 45 extending through said hollow member and bag are threaded within the apertures in the inner engaging member 44 to 10 firmly clamp each of said members to said bag. A port 46 is provided in each side of each of said cap screws which communicates with the hollow portion thereof to admit fluid under pressure into the bag 33 from the manifold 40. 15

It should be noted with reference to Figure 3 that projecting walls 47, 47, herein shown as being of an annular formation, surround each aperture in the hollow member 42 and abut the bag 33. In a like manner walls 49, 49 surround 20 each aperture in the inner engaging member 45 and project from said inner engaging member and abut the inner side of said bag. Thus, when the hollow member 42 and inner engaging member 44 are clamped to said bag, a fluid tight connection is provided from said manifold to said bag which firmly clamps said manifold to said bag and aids in preventing said manifold from being torn from said bag when subjected to extremely high pressures. 25

Means are provided to prevent expansion of the bag 33 beyond its full extent and thus prevent rupture thereof. As herein shown, said means includes a plurality of flexible chains 50, 50 encircling said bag for the entire length 35 thereof and connected together by suitable links 51, 51. At the section where said manifold engages said bag, said chains are connected to the upper and lower sides of said manifold by means of suitable rings 52, 52 secured to projections 53, 40 53 extending upwardly and downwardly from said manifold, as is best shown in Figures 5 and 6. It may thus be seen that when the bag 33 is subjected to extremely high pressure from the outside, as when breaking down the coal, and 45 these pressures are suddenly released when the coal is broken down, that the chains 50, 50 prevent expansion of the bag beyond a predetermined point, due to the continued pressure inside of the bag, and also prevent the manifold 50 49 from being torn from said bag.

The fluid pressure connections to said bag include a pipe 55 threaded in the manifold 40 and extending rearwardly therefrom, which leads from a port 55—a of a four-way valve 56, illustrated diagrammatically in Figure 8 and not herein shown or described in detail since it is no portion of my present invention. A pipe 57 leads from a port 57—a of said four-way valve to the high pressure side of a suitable fluid pressure 60 pump 58 while another pipe 59 leads from another port 59—a of said valve to the low pressure side of said pump.

A fluid pressure storage tank 60 is provided on the elevating frame 13 and a pipe 61 leads 65 therefrom to a port 61—a of the valve 56 to permit the pump 58 to withdraw fluid from said tank and transmit it to the bag 33 under pressure through the pipe 57, valve 56 and pipe 55. A by-pass valve 62 is provided in the system and is 70 connected between the tank 60 and a pump 58 to by-pass the fluid back into said tank through the pipe 61 when the valve 56 is turned in a position opposite from that shown in Figure 8 and fluid pressure is released from the bag 33. 75

The pump 58 is driven from the motor 23 by means of a spur gear 64 on a forward end of the longitudinal shaft 26 which meshes with and drives a spur gear 65 keyed on a sleeve 66, which sleeve is journaled in said support frame. The sleeve 66 may be selectively connected with a shaft 67 for the pump 58, for driving said pump, by means of a suitable jaw clutch 69 shifted through a suitable system of links and levers in a usual manner (not shown).

It may be seen from the foregoing that when the valve 56 is in the position shown in Figure 8, that fluid under pressure may be admitted to the bag 33, and that when said bag is inserted in the 15 kerf in the coal face, as shown in Figure 2, and pressure is admitted thereto, expansion of said bag will exert pressure against the coal to readily break it down.

It will now be seen that a new and improved 20 mobile coal breaking unit of a novel construction has been provided which is insertible in a kerf cut in the coal face for breaking down the coal by fluid under pressure, which unit is so arranged as to be readily transportable from place to place 25 and which may be inserted or withdrawn from kerf by power, and which is also adjustable so that it may be positioned at various points along the kerf or may be inserted in kerfs of varying heights.

30 While I have herein shown and described one form in which my invention may be embodied, it will be understood that the construction thereof and the arrangement of the various parts may be altered without departing from the spirit and 35 scope thereof. Furthermore, I do not wish to be construed as limiting myself to the specific embodiment illustrated, excepting as it may be limited in the appended claims.

I claim as my invention:

40 1. In a coal breaking apparatus, a fluid pressure coal breaking member which is substantially flat when in a deflated condition, means on one edge of said member adapted to admit fluid under pressure thereto, and means engaging the ends of 45 said member for supporting said member and inserting it into or withdrawing it from a kerf in the coal face, said means also forming a clamping means for closing the ends of said member.

2. In a coal breaking apparatus, a fluid pressure 50 coal breaking member which is substantially flat when in a deflated condition, means on one edge of said member adapted to admit fluid under pressure thereto, and means having supporting engagement with the ends of said member, said 55 means also forming a clamping means for closing the ends of said member and extending from a movable self-propelled truck for inserting or withdrawing said breaking member from the kerf by power.

60 3. In a coal breaking apparatus, a fluid pressure coal breaking member which is substantially flat when in a deflated condition, means on one edge of said member adapted to admit fluid under pressure thereto, and means having supporting 65 engagement with the ends of said member, said means also forming a clamping means for closing the ends of said member and being supported for lateral and vertical adjustment and extending from a movable self-propelled truck for inserting 70 said breaking member in a kerf at various positions therealong.

4. In a coal breaking apparatus, a truck, a fluid pressure coal breaking member which is substantially flat when in a deflated condition, means on one edge of said coal breaking member

intermediate the ends thereof for admitting fluid under pressure thereto, a pair of supporting members for said breaking member extending from said truck and mounted for movement with respect thereto in both horizontal and vertical 5 planes, and supporting connections between the ends of said supporting members and opposite ends of said breaking member.

5. In a mining apparatus, the combination with a movable supporting base, a fluid pressure coal 10 breaking member including a relatively flat hollow bag having opposed flexible walls adapted to be inserted in a kerf in a coal face, and a supporting connection between said base and said member whereby said member may readily be 15 inserted or withdrawn from the kerf or may be positioned at various points along the kerf comprising a turntable on said base, and a frame mounted on said turntable having supporting members projecting therefrom having supporting 20 engagement with the ends of said bag.

6. In a mining apparatus, the combination with a movable supporting base, a coal breaking member including a relatively flat hollow bag 25 having opposed flexible walls adapted to be inserted in a kerf in the coal face for breaking down the coal upon expansion of said member, and a supporting connection between said member and said base whereby said member may readily be inserted or withdrawn from the kerf 30 or may be positioned at various points along the coal face comprising a turntable on said base, and a frame mounted on said turntable having supporting members projecting therefrom having supporting engagement with and forming a closure 35 means for the ends of said bag.

7. In a mining apparatus, the combination with a movable supporting base, a coal breaking member including a relatively flat hollow bag 40 having opposed flexible walls adapted to be inserted in a kerf in a coal face for breaking down the coal upon expansion of said member, and a supporting connection between said member and said base whereby said member may readily be inserted or withdrawn from the kerf or may 45 be positioned at various points along the coal face comprising a turntable on said base, a frame mounted on said turntable for vertical movement with respect thereto, and supporting members projecting forwardly from said frame having 50 supporting engagement with and forming a closure means for the ends of said bag.

8. In an apparatus of the class described, a truck, fluid pressure coal breaking means disposed in advance thereof, and a supporting connection between said truck and coal breaking means for readily inserting or withdrawing said 55 breaking means from a kerf in the coal face comprising a turntable on said truck, a frame on said turntable mounted for vertical movement with respect thereto, a motor on said frame, a fluid pressure pump on said frame, a connection between said pump and coal breaking means for conducting fluid under pressure to said breaking means, a drive connection from said motor for elevating said frame with respect to said truck, another drive connection from said motor for driving said pump, and projecting supporting members extending from said frame having supporting 65 engagement with said coal breaking means.

9. In a coal breaking apparatus, a flexible coal breaking member having flexible side walls which are substantially flat when in a deflated condition but which may be expanded to a relatively 75

circular formation, and a fluid tight connection on one edge of said flexible breaking member adapted to admit fluid under pressure thereto comprising an inner member having a plurality 5 of openings therein adapted to register for engagement with corresponding openings in said flexible member, a projecting wall surrounding each open portion of said inner member, said walls being adapted to engage said flexible member 10 and surround the open portion thereof, a manifold on the outer edge of said coal breaking member having a plurality of openings therein adapted to register with said first-mentioned openings, a projecting wall surrounding each 15 open portion of said manifold and adapted to abut said flexible member, and means for securing said manifold and member together to engage said walls with said flexible member, said means also forming a means for admitting fluid 20 under pressure to said flexible member.

10. In a coal breaking apparatus, a fluid pressure coal breaking member having flexible side walls which are substantially flat when in a deflated condition but which may be expanded to 25 a relatively circular formation, and means on one edge of said member adapted to admit fluid under pressure thereto comprising an inner engaging member engaging the inside of said edge 30 of said bag and having a plurality of openings therein adapted to register for engagement with corresponding open portions in said flexible member, a projecting wall surrounding each open portion of said inner member and adapted to engage said flexible member and surround the open 35 portion thereof, a manifold on the outer edge of said coal breaking member having a plurality of openings therein adapted to register with said first-mentioned open portions, an annular wall surrounding each open portion of said manifold 40 and adapted to abut said flexible member, and means for securing said manifold and member together to engage said walls with said flexible member comprising bolts having ports therein leading from said manifold to the inside of said 45 breaking member.

11. In a coal breaking apparatus, a flexible coal breaking member having flexible side walls which are substantially flat when in a deflated condition but which may be expanded to a relatively circular formation, and means on one edge of said member adapted to admit fluid under pressure thereto comprising an inner member engaging the inside of said edge of said bag and having a plurality of openings therein adapted 50 to register for engagement with corresponding openings in said flexible member, a projecting wall surrounding each open portion of said inner member and adapted to engage said flexible member and surround the open portion thereof, a manifold on the outer edge of said coal breaking member having a plurality of openings therein adapted to register with said open portion in

said bag, an annular wall surrounding each of said open portions and adapted to abut said flexible member, and means for securing said manifold and member together to engage said walls with said flexible member comprising bolts having ports therein leading from said manifold to the inside of said breaking member and being threaded within the openings in said inner member. 5

12. In a coal breaking apparatus, a coal breaking member having expansible side walls which are substantially flat when in a deflated condition, means on one edge of said member for the admission of fluid under pressure thereto comprising a member on the inner side of said coal breaking member having a plurality of openings therein and having an annular projection encircling each of said openings and adapted to abut the inside of said coal breaking member and encircle corresponding openings in said member, a manifold on the outer side of said coal breaking member having openings therein with annular projections encircling the same and adapted to be positioned in alignment with said first-mentioned openings, and means for securing said member and manifold to the edge of said breaking member comprising bolts extending through said openings in said manifolds and being threaded in said inner member, said bolts having ports therein to admit fluid under pressure to said breaking member from said manifold and being adapted to clamp said annular projection to said flexible edge of said breaking member. 10 15 20 25 30

13. In a coal breaking apparatus, a fluid pressure coal breaking member having flexible side walls which are substantially flat when in a deflated condition but which may be expanded to a relatively circular formation, and means on one edge of said member adapted to admit fluid under pressure thereto comprising an inner member having a plurality of openings therein adapted to register for engagement with corresponding openings in said flexible member, a projecting wall surrounding each opening of said inner member and adapted to engage said flexible member and surround the open portions thereof, a manifold on the outer edge of said coal breaking member having a plurality of openings therein adapted to register with said first-mentioned openings, an annular wall surrounding each of said openings and adapted to abut said flexible member, means for securing said manifold and member together and engaging said annular walls with said flexible member, and means to prevent pressure in said breaking member from tearing said inner member and manifold therefrom comprising inelastic flexible members secured to said manifold and encircling said breaker member to limit expansion thereof beyond a predetermined point. 35 40 45 50 55 60

THOMAS E. PRAY.
